UNITED STATES PATENT OFFICE.

ISRAEL HOGELAND, OF CHICAGO, ILLINOIS.

APPARATUS FOR FORGING TIRES.

SPECIFICATION forming part of Letters Patent No. 518,815, dated April 24, 1894.

Application filed June 20, 1893. Serial No. 478,283. (No model.)

To all whom it may concern:

Be it known that I, ISRAEL HOGELAND, a citizen of the United States, residing at Chicago, in the county of Cook and State of Illinois, have invented a new and useful Improvement in Apparatus for Forging Metal Tires, of which the following is a specification.

The object of my invention is to provide a novel apparatus for forging annular metal blanks into flanged tires for car-wheels, whereby great saving in time and handling, and consequent reduction in the expense of manufacture, shall be secured.

According to my improvement I provide a blank and fasten it in place in a holding die in a manner to leave the upper annular edge free to be heated, prior to bending it. To heat the blank, I provide an annular steel body adapted to fit upon the upper exposed edge of the blank, and which is encircled by an electric induction coil, whereby when the coil is charged from a suitable electric generator (dynamo) the annular body will be quickly heated to a high degree about its edge-portions, and with the heater in place, the heat is quickly conducted to the adjacent upper edge-portion of the blank. On then removing the annular electric heater, a suitable die is applied to the exposed heated edge of the blank and force (such as that of a trip-hammer) is applied to the upper die to produce desired bending of the edge-portion of the blank. When one edge of the blank has been thus treated, the blank is removed and readjusted in a holding die to expose its opposite annular edge for similar treatment.

My improved apparatus is illustrated in the accompanying drawings, in which—
Figure 1 is a longitudinal sectional view of that portion of the apparatus carrying the holding dies for the two forging operations on the blank, which is shown adjusted in each die. Fig. 2 is a sectional view of the upper die for the first forging operation, and Fig. 3, a similar view of the upper die of the second forging operation. Fig. 4 is a cross-sectional view of the annular electric heater. Figs. 5 and 6 are cross-sectional views respectively of my improved blank and of the tire forged therefrom.

A is the bed of the apparatus having the vertical openings A' and A².

B is a holding die formed of an annular metal (steel) body e flanged at its base and fastened by bolts b at the flange-portion to the upper side of the bed A about the opening A'; and seated on the bed within the annular body is the core C, recessed about its periphery to correspond with the shape of and receive between it and the surrounding said annular body, the blank K, which is rounded at its opposite edges, respectively from the outer to the inner circumference and from the inner to the outer circumference, as indicated at x and x'. About the upper edge of the core C is formed an offset c into which to bend the upper projecting edge portion of the blank K, as hereinafter described. Centrally from the lower side of the core C extends, in the opening A', a stem g connected by a link m with one end of a lever n fulcrumed at t and projecting normally at its handle or pedal portion o above the plane of the bed A.

B' is the second holding die formed of the annular metal (steel) body e' flanged at its base and fastened by bolts b' at the flange-portion to the upper side of the bed about the opening A² and about a shoulder c² at the upper end of the opening, the shoulder affording a seat for a movable head G having a central stem g' extending downward in the opening A², wherein it is connected by a link m' with one end of a lever n' fulcrumed at t' and extending as to its handle or pedal portion o' like the lever n. About the inner upper edge of the annular body e' of the die B' is formed an offset c' into which to bend outwardly, as hereinafter described, the edge-portion x' of the annular blank after having undergone the first operation, in which condition it is indicated in the holding-die B' in Fig. 1, by the reference K'. The core C' of the die B' fits inside the annular body e' to leave sufficient space between the two for the partly finished body K', and has formed about its lower edge an offset c², to receive the inward extending flange q formed on the blank K by the operation with the die B. I also provide the core C' with a handle f.

D and D' are the forging dies, each com-

prising a block having an upper head h against which to exert the blows of the forging implement (preferably a trip-hammer, not shown, but which may involve any suitable or well-known construction), and each being provided, also, with a swinging bail h' by means of which to handle it, as through the medium of a suitable crane. In the base of the die D , which is recessed about its center, as shown, is formed, about the recess, a shallow offset d having the flange-portion d' about its exterior; and in the base of the die D' , which is also recessed about its center, is formed an offset d^2 having the flange-portion d^3 about its inner edge.

15 I is the electric heater comprising an annular steel body having wound about it an induction coil i , properly connected for charging with a dynamo (not shown).

20 The operation is as follows: The blank K is adjusted in the holding-die B in the position illustrated, when the heater I is imposed on its upper edge x and the electric charge is passed through the coil i and produces rapid 25 heating of the annular body, the edges of which soon become reduced to a white heat; and the projecting portion of the blank is rapidly heated similarly by contact with the adjacent edge of the heater, whereupon the 30 heater is removed and the die D is adjusted on the die B , fitting inside the annular body e . Then the trip-hammer is actuated to pound the die D and forge the blank to produce the flange q by bending the upper edge of the blank inward into the offset c . On raising the die D , the lever n is operated to force the core C out of the die B to permit withdrawal 35 of the blank in the form in which it is shown in the die B' . It is adjusted in the last-named holding die with the flange q engaged between the offset c^2 about the base of the core C' and the head G . On the then projecting annular edge x' of the blank K' is thereupon imposed the heater I , which is caused, in the 40 manner described, to heat that edge of the blank; when, upon removing the heater, the die D' is lowered to bear against the blank and a trip-hammer is actuated to forge the edge-portion x' into the outward-extending flange p by bending it into the offset c' . The 45 result is a tire L , the flange p of which forms the wheel-flange at the inner edge of the tread of the wheel, the flange q forming the outer abutment for the wheel-center about which the tire is fitted. On thus finishing the forging operation, the lever n' is operated to raise the head G and parts imposed upon it out of the die B' to permit the tire to be removed on withdrawing the core C' .

50 By means of my improvement much time and handling are saved, the provision of the heater adapted to be removably applied to the tire-blank and heated while seated thereon to impart its heat to the blank, rendering the

operation obviously very rapid by avoiding 55 the delay in time and inconvenience in handling incidental to the old method of inserting the blank into a fire for heating it and adjusting it into the dies while hot.

What I claim as new, and desire to secure 70 by Letters Patent, is—

1. In a tire-forging apparatus, the combination of a die for holding a tire-blank, a removable electric heater placed on the blank in the die, and a forging-die, substantially as 75 and for the purpose set forth.

2. In a tire-forging apparatus, the combination of a base A having seated thereon tire-blank holding-dies B and B' , an electric heater I , comprising an annular metal body 80 surrounded by an induction-coil i and adapted to be heated by electricity, and to seat on the edge of a tire-blank, and forging-dies D and D' for the respective holding-dies, substantially as and for the purpose set forth. 85

3. In a tire-forging apparatus, the combination of a base A , having seated thereon tire-blank holding-dies B and B' , formed, respectively, with stationary annular bodies e and e' and removable cores C and C' , an 90 electric heater I , comprising an annular metal body surrounded by an induction-coil i and adapted to be heated by electricity, and to seat on the edge of a tire-blank, and forging-dies D and D' for the respective holding-dies, 95 substantially as and for the purpose set forth.

4. In a tire-forging apparatus, the combination of a base A having seated thereon tire-blank holding-dies B and B' , the die B comprising a stationary annular body e and removable core C having an offset c , and the die B' comprising a stationary annular body e' having an offset c' , a removable head G seated on said base and a removable core C' having an offset c^2 , an electric heater I , and forging-dies D and D' for the respective holding-dies, substantially as and for the purpose set forth. 100

5. A tire-forging apparatus comprising, in combination, a base A provided with openings A' and A^2 and having seated at the openings tire-blank holding-dies B and B' , the die B comprising a stationary annular body e and removable core C having an offset c and provided with a stem g having linked to it a lever n , and the die B' comprising a stationary annular body e' having an offset c' , a removable head G provided with a stem g' having linked to it a lever n' and a removable core C' provided with an offset c^2 , an electric heater 110 I , and forging-dies D and D' for the respective holding-dies, substantially as and for the purpose set forth. 115
